HEADGEAR CHIN STRAP

Filed Dec. 2, 1941

FIG. 1.

FIG. 2.

FIG. 3.

INVENTOR:—

HAROLD J. LYON.

By Earl D. Moore ATTY.

UNITED STATES PATENT OFFICE

132,184

DESIGN FOR HEADGEAR CHIN STRAP

Harold J. Lyon, Los Angeles, Calif.

Application December 2, 1941, Serial No. 104,437

Term of patent 7 years

To all whom it may concern:

Be it known that I, Harold J. Lyon, a citizen of the United States and a resident of the city of Los Angeles, in the county of Los Angeles, and State of California, have invented a new, original, and ornamental Design for Headgear Chin Strap, of which the following is a specification, reference being had to the accompanying drawing, forming part thereof.

In the drawing:

I claim:

The ornamental design for a headgear chin strap, substantially as shown.

HAROLD J. LYON.
